CLAIM

The ornamental design for an adjustable bag rider with angled bolt, as shown and described.

DESCRIPTION

FIG. 1 is a PERSPECTIVE view of a design for the adjustable bag rider with angled bolt;

FIG. 2 is a SIDE view thereof;

FIG. 3 is a SIDE view thereof;

FIG. 4 is a FRONT view of thereof;

FIG. 5 is a BACK view thereof;

FIG. 6 is a TOP view thereof; and,

FIG. 7 is a BOTTOM view thereof.

The two circular features located on the front, top portion of the angled bolt on adjustable bag rider are intended to be through holes and form a part of the claimed design.

The broken lines in the drawings illustrate portions of the angled bolt on adjustable bag rider and form no part of the claimed design.
